2,481,531

FITTING FOR LIGHTING FIXTURES

Paul D. Phillips, Hendersonville, N. C., assignor
to Benjamin Electric Mfg. Company, Des
Plaines, Ill., a corporation of Illinois

Application July 11, 1945, Serial No. 604,338

23 Claims. (Cl. 240—41.55)

1

This invention relates particularly to covers to complete the enclosure of circular reflector or housing type lighting fixtures which comprise essentially a pressed, flat or formed glass with means to gasket or seal the glass over the open end of the housing and means to clamp or secure the glass to the housing. They may be of a type that is an entirely separate device capable of being attached or detached from the lighting unit at will or of a type that is a permanent part of the unit, or "built in," and not intended to be regularly, entirely removed. In both types, the cover per se must be openable for lamp changing and reflector servicing, and in the detachable type the housing or fixed element must be capable of securely gripping the housing for the cover and clamping elements are dependent on it for support.

The present invention is an improvement upon such devices, and besides overcoming faults therein introduces new features of advantage to manufacturer, installer and user.

The usual practice is to locate the seal gasket between the housing rim and the top edge surface of the glass, and clamping them together to form the seal. This puts the glass under strain and, to make it worse, this strain is unequally distributed, since the clamps are spaced at intervals around the glass or its frame. Attempts have been made to overcome the difficulty, but it is done by separately gasketing the glass and frame, the frame gasket being outside or beyond the edge of the glass, resulting in a wide section frame built at the expense of a reduced diameter of clean light opening through the light or an oversize housing rim or both, and the difficulty increases with larger sizes.

In the present invention, and that is one of its objects, the glass is of full size of the housing or rim, is cushion-mounted in its frame and is wholly free from clamping strain, the clamping strain is all taken by the metal frame and may be increased as is necessary for the larger sizes without imparting it to or endangering the glass, and the frame and metal cover parts are reduced to the barest essentials in horizontal cross-sectional proportions, with resulting minimum of blocking or covering of light opening through the glass or obstruction of effective reflecting surfaces of the reflector.

A further object of the invention is the provision of a cover construction having a novel method of positioning and fixing the gasket in the housing stationary element of the construction, and not in the movable cover element,

2

whereby a minimum cross-section of gasket and of a single size for all sizes of reflector or housing rim seats may be used, which is definitely fixed in a position on the stationary element where it cannot help but contact the seal surface or seat of the movable cover element when the latter is closed, which is accurately positioned on the narrow rim of the housing and held thereon at all times to form a perfect seal therewith, and which is not lost, displaced, creased, wrinkled or disturbed in any way in its proper positioning by the opening of the cover, the servicing operations, and the re-closing and clamping of the cover, or in any other way.

Another object of the invention is to produce a detachable cover construction having the advantages mentioned which may be readily and properly installed or applied to reflectors or housings already in use, regardless of their variations in size and by unskilled labor without the use of special tools and in a natural manner as suggested by the device itself.

A manufacturing tolerance or variation in diameter of the open ends of reflectors is permitted in commercial practice. For an 18-inch diameter reflector, for example, as here represented in the drawings, the allowance is 3/16 inch—1/32 less than normal and 5/32 over normal. The manufacturer ordinarily does not know the exact size of the reflector or housing to which the cover will be applied. The user is not likely to know the exact size of his fixtures in use, other than the general size designation—18-inch, for example.

Further and several objects of the invention are to provide a cover construction of the type mentioned having an expansible gasket-retaining means adaptable to the different sizes of rim due to manufacturing tolerances and which may be applied merely by pushing the stationary element up over the rim of the housing or reflector and then tightening the retaining band by the single thumbscrew provided; to provide a device to be mounted on varying diameters of reflectors or housings with distributed and preferably with controlled gasket stretch; to provide a device having a "tailor-made fit" to varying diameters of units served; to provide a seal gasket that is a part of the stationary element which is attached to the reflector and definitely fixed in position so that it cannot help but contact the seal surface of the movable cover element; to provide a device of the character described in which the cover element is readily unhookable from the upper or reflector element for ease of

handling and installation and for convenience in the removal of the glass for washing or replacement; to provide a device of this nature which reduces the operable fastening means of the complete device to a reflector or housing to a single captive thumbscrew and provides a single enveloping band to conceal and draw together, in a chuck-like manner, the several gasket-retaining and positioning parts, closely gripping the reflector and forming a rigid, substantial anchorage for the movable cover element; to provide a square or rectangular cross-section gasket depending on its attachment and positioning to a narrow rim on a thin metal piece whose tongues pass through perforations or slits in the gasket section; to provide an expansible gasket-retaining means divided into a series of segments and whose separation is controlled or limited by a perforated strip engaging the tongues of the segments and preferably serving also as a side wall to keep the gasket in place and form; to provide a gasket mounting means in which a series of springs act both to open the enclosing band when freed and to support and space the retainer segments when the band is closed, and to provide a detachable hinged water- and dust-tight cover construction in which the cover element centers inside of and is enclosed by the means by which it is supported on the reflector.

Further objects and advantages will appear from the description and claims to follow, in connection with the accompanying drawings which illustrate, by way of example and not of limitation, a "built in" and a detachable cover construction, and in which—

Fig. 1 is a plan view of the "built in" form of the cover construction as applied to a reflector or housing, assuming the same to be overhead and opening downwardly;

Fig. 2 is a side elevation of the same, the body of the housing being broken away and the movable cover element being shown partly open in full lines and closed in dotted lines;

Fig. 3 is a detail cross-section through the rim of the housing and cover construction, taken on the line 3—3 of Fig. 1, and being at substantially full scale;

Fig. 4 is a similar detail view on the line 4—4 of Fig. 1 with the pivot bolt-head removed;

Fig. 5 is a similar view on the line 5—5 of Fig. 1;

Fig. 6 is a detail perspective view of a portion of the gasket and of the gasket-retaining ring, showing the tongues of the latter bent up horizontally to receive the gasket thereon and before they are bent upwardly on the inside of the gasket;

Fig. 7 is a plan view similar to Fig. 1, but on reduced scale, of the detachable cover construction as applied to a housing or reflector;

Fig. 8 is a side view of same, similar to Fig. 2;

Fig. 9 is a detail cross-sectional view on line 9—9 of Fig. 7;

Fig. 10 is a similar detail view on line 10—10 of Fig. 7;

Fig. 11 is an exploded view of the parts of the gasket ring; and

Fig. 12 is a view similar to Fig. 9, but with the outer securing band expanded.

Referring first to the form shown in Figs. 1 to 6, which illustrate a circular reflector with a non-detachable or "built-in" cover, such as may be used in outdoor flood-lighting or other places where it is desired that the lights be sealed against dust, smoke and moisture due to rain, mist, fog or other causes, the open end of the reflector housing 20, which may be of aluminum, steel or other

suitable material and of the usual or desired type, may be provided with a flat or rectangular rim formed outwardly, as at the ledge 21, Figs. 3 and 4, thence downward as at the flat or straight outer side 22, and then inwardly as at the flange 23. This rim reinforces the edge of the housing and provides means for applying and attaching the gasket thereto for sealing the light.

The gasket 24, preferably square or rectangular in cross-section and of woven asbestos composition, a well-known material for the purpose, or other suitable material, is seated up against the lower face of flange 23 of the rim of the housing and is permanently attached thereto. Such gasket strips come in rolls, and the correct length may be cut off and fitted to and around the rim of the particular housing so that no gap appears at the tightly butted ends of the gasket or elsewhere.

The gasket is held to its said seat in the housing by a thin metal strip or endless band or ring 25, also preferably of aluminum, which is closely fitted to the outer rim surface 22 and may be riveted thereto and serves as a housing armor band as well as a gasket retainer. This band is curved inwardly at the upper edge 26 over the rim ledge 21. The opposite edge of this band 25 is notched or cut away to form tongues 27, Fig. 6, which are bent to stand inwardly at right angles to the body of the band. These tongues are adapted to be passed through slits 28 formed in the gasket 24 to hold the same up tightly against its seat 23 on the rim of the housing, the butted ends of the gasket being located between two of the tongues, and preferably diametrically opposite to the butted ends of the notched ring. These tongues do not interfere with the compression of the gasket between its upper and lower seats and are tightly fitting in the slits to preserve the seal through the gasket. After the gasket has been slipped in place on the tongues, the latter are bent upwardly, as indicated at 29 in Figs. 3 and 4, on the inner side of the gasket to hold the same in place on the tongues and on its seat 23. Holes 30 may be formed in the tongues to insure their being bent upwardly at the proper points by merely applying upward pressure on the ends thereof.

The result of this construction and arrangement is that a suitable gasket is readily applied to the housing in a practical and rugged manner and remains as a part thereof regardless of the opening and closing of the cover, as hereinafter explained. The dimensions may be varied, but it may be said by way of explanation, though not of limitation, that with a gasket of $\frac{1}{4}$ -inch square cross-section and the tongues and slits spaced on $\frac{5}{8}$ -inch centers, the slits being $\frac{3}{8}$ -inch long and the tongues $\frac{3}{32}$ -inch wide, as indicated, satisfactory results have been obtained. By this means the minimum cross-section of gasket may be used and of one single size for all sizes of reflectors and styles of reflector rims or housing gasket seats. With a housing rim, for instance, of circular bead form instead of flat, and of the usual size of just under $\frac{1}{4}$ -inch in diameter, the same gasket seats equally well, the unnotched ring portion lying against the outside of the rim and the row of upturned tongues on the inside forming a substantially perfect centering of the gasket on the rim, and proper disposal of the included gasket results.

The cover includes a circular frame and the glass roundel carried thereby. The frame carries the glass at all times so that it cannot fall out

when the cover is opened and suspended by the hinge or at other times. It is cushioned-sealed therein. The frame causes a sealed connection between cover and housing to be made at the gasket when the cover is clamped in its closed position and the gasket is compressed. The frame itself carries the strain without putting the glass under compression or subjecting it to any strain thereby. The rim of the housing, the gasket and glass are all substantially of the same diameter so that light from the lamp and from the effective reflecting surfaces of the reflector are not obstructed. The frame, moreover, does not project unduly inside the periphery of the glass and thus reduce the clean light opening through the glass.

The cover frame, indicated generally at 31, in the form here illustrated, is preferably a continuous ring of sturdy cross-section, shown cross-hatched in Figs. 4 and 5, which may be of cast aluminum or other suitable material or drawn from heavy gauge sheet metal. The peripheral edge of the glass 32, which may be molded, flat plate, curved sheet or as desired, lies upon a slightly elevated inner horizontal ledge 33, near the bottom of frame ring 31, and the substantial space between the edge of the glass and the outer portion of ring 31 is filled with a suitable calking cement 34, preferably a high heat-resisting, non-setting, surface-adhering cement or sealing compound, which completely fills and seals such space and cushions and holds the glass sealed in the frame without the use of rigid mechanical clamping means.

Into this plastic seal is forced the vertical leg of a continuous sheet metal seal ring 35, which penetrates the sealing cement 34 to the bottom and its edge rests against the frame member 31. The inwardly extending horizontal leg 36 of the ring 35 is disposed over and above the rim of the glass 32 and does not touch it. The upper or horizontal surface of this leg 36 of metal ring 35 forms the lower seat for the gasket 24 when the cover is closed. The ring 35 itself is sealed to the lower part of the frame 31 by the same plastic cement 34 as the glass.

To insure the glass remaining in position below the seal ring 35-36, a small, soft asbestos rope filler 37, of a size best to fit the particular glass in each assembly, is placed in the corner between the vertical and horizontal legs of the seal ring 35 before the insertion of the ring into the plastic seal 34. The seal ring 35 may be centered in the frame 31 by several hemispherical embossments 38, Fig. 3, formed in the vertical leg of the ring 35 and suitably spaced thereabout. The glass 32 may be centered in the frame 31 by a suitable jig at the time of assembly therein, and maintained in its centered position by the cement itself.

If desired, the horizontal leg 36 of seal ring 35 may be flat on top throughout its width, as shown in Fig. 5, but may be turned up at its inner edge 39, as shown in Figs. 3 and 4, to engage and be pressed into the bottom of the gasket 24 when the cover is closed and clamped shut to form the seal.

Also, if desired, to doubly insure against any possible dislodgment of the glass or seal ring in the frame, the arrangement of Fig. 5 may be provided, wherein a light-gauge, flat spring member 40 is shown screw-attached at its upper end to the upper edge of frame ring 31 and extends downwardly and is riveted at its lower end to the seal ring 35. Three to six of these, suitably spaced about the ring, suffice.

With the construction described, the glass and sealing ring are sealed in the frame, and when the cover is closed on the housing, the two are sealed at the gasket between the gasket 24 on the housing and the seating seat 36 of the sealing ring 35 in the cover frame.

The gasket is sealingly compressed between its said seats above and below, the one, 23, in the housing and the other, 36-39, in the cover, preferably by suitable clamps properly spaced about the same. In an 18-inch housing, about seven clamps of the type to be described, spaced equally about the ring, have been found to give satisfaction, but the number and type may be varied as desired, a smaller housing requiring a less number and a larger may need more. With the construction described, the glass being entirely free from the clamping stress, a positive, spaced clamping means may be used with entire safety.

Here, as shown in Figs. 1, 2, and 3, the frame ring is provided with suitable embossments 41 at the appropriate places, in which a clamping thumbscrew 42 is threaded to operate an automatic self-adjusting clamp plate 43, which in closed position fulcrums on the outer upper edge of the embossment 41 and is clamped down at the other end on top of the upper edge of the housing rim and flange or inturned edge 26 of the gasket retaining ring by tightening the thumbscrew 42. A depending tail 44, Figs. 1 and 2, at the rear or outer end of clamp plate 43, strikes the lug 45 at the outer side of boss 41 when the plate 43 swings to its closed position. When the plate swings to its open unclamped position substantially parallel with the frame, the tail strikes against the side of the boss or a lug 46 thereon and stops the plate in that position. The thumbscrew causes the plate to swing automatically in this way in both the initial closing movement and in the opening movement in the natural turning of the screw to clamp and unclamp the cover to and from the housing. This is accomplished by a suitable spring or friction washer connection of the screw 42 with the plate 43, whereby the screw frictionally engages the plate sufficiently to turn the same in either direction when the plate is free to turn, but may be turned further therein when the plate is blocked from turning. A suitable spring within the top recess of the boss and around the screw presses upwardly against the washer connection and thus against the plate to keep it in raised position at all times and to prevent rattling and the plate tending to move to open position due to vibration or the like. This type of clamp is disclosed in Leinen Patent No. 2,285,728, of June 9, 1942, to which reference may be had for further details.

The cover may be hinged to the housing as desired or as indicated in the drawings where two hinge brackets 50 are shown riveted or otherwise secured on the outside of the gasket retaining rim 25 and rim of the housing 20. Co-operating hinge members 51 are formed in any desired way on the frame ring 31 of the cover. These are connected by the screw bolts or hinge pins 52 suitably sleeved for their passage through the hinge members 51 and threaded into the members 50. The sleeves on the pin also suitably space the heads of the bolts from the hinge member 50. The apertures 53 for the pins 52 through the hinge members 51 are considerably larger than the pins, to give freedom of independent movement of the frame 31 in being clamped to and unclamped from its seat on the gasket and permitting it to move in a direction perpendicular to the seat in

seating and unseating, and to take care of slight variations in dimensions incident to manufacture.

By this construction the cover is sealingly clamped in closed position independently of the glass so that the latter is not subjected to strain thereby; the glass is of full size and the supporting frame is comparatively small so that the light from the housing is not obstructed or the frame unduly enlarged; the gasket is carried on the housing stationary element in fixed relation to the narrow rim seat, and therefore may be comparatively small in cross-section and is not disturbed by the opening of the cover, and always finds a sealing seat on the cover element regardless of slight variations in positions that may occur for various reasons; the gasket is retained on the rim by the retaining ring provided with the impaling pins or tongues passing therethrough and mechanically supporting and holding it to its narrow seat on the rim without affecting its compressibility and sealing capacity on and between its seats; and the cover is most conveniently clamped in sealing position and condition or unclamped and opened for cleaning and servicing purposes.

The foregoing form of device is such as may be made as a unit in the factory, where all parts can be made to agree, but many lighting fixtures have been and are being put into use where, for one reason or another, covers are not provided for the reflectors or housings as built and installed and the users later desire to apply suitable sealing covers thereto. But such devices are apt to vary slightly in diameter at the open end, so much so that a recognized tolerance in an 18-inch-diameter reflector, for example, is $\frac{3}{16}$ -inch— $\frac{1}{2}$ less than normal and $\frac{5}{8}$ over normal. The manufacturer of the covers, however, for such later installations does not know the exact size of the reflectors or housings the covers may be called upon to fit.

In all these covers, it is desired that the gasket mounting element fit the reflector or housing rim exactly, and when the closing means are drawn up that it form a tight, rigid part of the fixture. It is not intended to be riveted or permanently secured to the housing as in the "built in" form of Figs. 1 to 6. The toggle or equivalent latches that pull the openable cover element up tight and squeeze the gasket seal in so doing are dependent for their support on the framework of this gasket mounting element as a whole. Moreover, such elements are usually attached to the reflectors of the installed fixtures at the customer's plant by someone not familiar with the construction of the device, so they must be built so that they are not only easy and practical to apply to the installed fixtures, but the method of doing so and their attachment to the reflector must be obvious from the construction.

In carrying out this feature of the invention, provision is made at the factory for building the upper gasket mounting element around a circular jig of the same diameter as that of the minimum diameter reflector under the tolerances allowed for that size of standard reflector. Provision is made, in the mounting so built, for permitting the metallic parts thereof to expand and the gasket to stretch uniformly to fit a reflector of any larger size within the allowable range, and to do so automatically in the ordinary, usual and natural acts of applying same to the reflectors.

In this universal form of the invention, an embodiment of which is shown in Figs. 7 to 11, the reflector or housing is indicated at 60 and

5 61 the bead rim at the open end at 61. The gasket 62 is the same as in the first-described form and is cut to the length required for the minimum diameter of reflector of that size. The gasket is slit, as in the first instance, to receive the tongues 63 on the gasket retainer strip or ring 64, which tongues are bent upwardly on the inner side of the gasket after the latter has been threaded thereon definitely to confine and hold the same in place. The gasket-retaining strip 64 is engaged the outer face of the reflector bead 61 when the mounting is in position on the housing and thus holds the gasket in place with respect to the bead. The upper edge of the gasket-retaining strip is bent outwardly, as at 65, for strengthening purposes and to assist in applying the device and in supporting the strip, as will be explained.

An outer band 66 surrounds this construction 20 and has a horizontal leg 67 overlapping the reflector bead 61 and supporting this mounting when the device is attached to the reflector. This band is continuous except at one point where its 25 separated ends 68 (Fig. 7) are bent outwardly and are suitably connected by a comparatively long thumbscrew 69, which is preferably made captive in the end near the thumb wing as by a suitable groove and spring clip and by which screw the band may be drawn tightly about the housing and over the rim or expanded.

In order to make the gasket mounting 30 expandable to adapt it to the larger sizes, as much, say, as 3/16-inch larger in diameter than the jig to which it is fitted at the plant, the tongued gasket-retainer strip or ring 64 is cut into or 35 made in several segments, six substantially equal segments being satisfactory for an 18-inch reflector, as shown in Fig. 11, where one of the segments is shown extending between the points 69^a and 70, and the remainder of the ring is 40 divided accordingly. These segments are mounted so as to be moved in and out or radially toward and from the center of the ring to the extent required to fit the ring to the different diameters 45 of rims, each segment being supported substantially at its center by the headed pin 71, Fig. 9, riveted or otherwise secured thereto and extending outwardly through and slidably in an elongated horizontal slot 75 (Figs. 7 and 9) or hole in 50 the outer band 66. The segments are pressed inwardly toward the reflector bead by strong flat or leaf spring strips 72, six of them, overlapping the ends of adjacent segments, Figs. 7 and 11, and bearing at their ends thereon. This spring 55 72 is riveted or secured at its center to the outer band, as at 73. These springs 72 also support the segments, since their free ends extend under the flange or outward bend 65 of the gasket-retaining rings and they are riveted at their centers to 60 the outer band 66. These springs 72 serve also as expander springs for the outer band 66 when the thumbscrew 69 is loosened in the operation of attaching the gasket-retainer element and 65 mounting to a reflector. They cause the outer band to open and expand uniformly around the circle.

This outer band can expand only to the limit of the heads of the shouldered pins 71, but this is sufficient to let the inner edge of the horizontal leg 67 move outwardly to clear the reflector bead when the device is pushed up over or removed from a reflector. This, as shown in Fig. 12, lines up the said inner edge flush with the inner face of the gasket-retaining strip or ring 64 of the segments, and of the control or limit strips 74,

to be described, which however are very thin. In the further expansion of the outer band, when the device is pushed up over the larger diameter housing rims, as explained, the pins 71 slide longitudinally in the slots 75 in the outer band, during this outward movement of the segments, to the extent necessary therefor, it being recalled that the flat springs 72 cause the outer band to expand equally around all the segments and continue to press on the ends of the segments during this bodily movement of the segments. The segments, therefore, tend to move in and out radially.

In this outward movement of the gasket-retaining segments, the gasket 62, which is threaded on the tongues of the retaining strip segments, is caused to stretch slightly, but this is distributed over a multiple number of points (six in the 18-inch size illustrated). While the gasket normally stretches uniformly at the said points and keeps the segments moving radially, it is preferred to control the movement of these tongued gasket-retainer segments so that when they are expanded to the full over the maximum diameter, their movement will be equalized and uniform and along radial lines and their spacing equalized, and the gasket will not be overstretched at any point. Accordingly, a thin flexible metal strip 74, Fig. 11, having slots on the same centers as the tongues 63 of the gasket-retaining strip 64 but slightly longer than the width of the tongues, is slipped over the tongues of adjacent segments so as to bridge the gap between segments. This is done before the gasket is applied to the tongues, Fig. 10. The slots in this retainer segment limit strip should be longer than the width of the tongues by as much as the difference in length between minimum and maximum circles at that location divided by the number of joints or gaps between segments so bridged, six in this instance. The number of tongues engaged on each segment may be more or less, but five on each are shown so engaged by the limit strip and have been found satisfactory. Consequently, the gasket is not overstretched at any point, even when the device is being attached and the outer band is expanded fully.

In attaching the device to a housing, it is, of course, necessary that the outer band be expanded sufficiently to enable it to pass over the reflector rim when being pushed up into position on the housing. If that is of the smallest size, the segments are not necessarily disturbed. If larger, they are pushed out to the extent necessary by the act of pushing the device up into place. Normally, the one attaching the device in the field does not know the exact size of the rim housing. But he does know that the device is to be opened or expanded by unloosening the screw 69 in order to push it up over the rim of the housing. He therefore unscrews it from the end 68 of the band which leaves the band free to expand under the influence of springs 72 when the gasket stretches.

A simple 'push-on' the gasket assembly then pushes it up over the bead of the reflector. If the rim encountered is the smallest size, no change in segments or gasket occurs; if the rim is larger, the segments are moved outwardly by it and the gasket slightly stretched in the several areas adjacent the segment joints. The thumb-screw is then inserted and operated to tighten the outer band over the rim and segments and about the reflector. In this movement, the springs 72 tend to push the gasket-retainer seg-

ments up tightly against the reflector bead, the pins 71 sliding laterally in their slots to the slight extent necessary, the gasket is held in proper position with respect to the rim, and the cover, if hung, is ready to be closed and clamped in that position, as will be explained. The gasket is thus a part of the housing element, and not of the cover element of the device.

The cover construction in this form of the invention is much like that of the first form described, particularly in that the glass is not put under stress by the sealing clamping action, is of full size, and is held in its frame by the sealing, cushioning, and calking cement rather than by mechanical clamps. The glass is of full size and the frame of minimum proportions. The glass-enclosing frame member 80 is preferably a continuous ring of suitable drawn-metal type having an inturned ledge 81 upon which the glass rests but is otherwise spaced therefrom, the space being filled with a suitable calking cement 82, such as before described, and which extends up over the upper edge of the glass as indicated. A stiff sealing ring 83, angular in cross-section, has its vertical leg telescoping closely over the inner ring 80 and which may be coated on its inner surface with a paint or other liquid that will harden by drying, to form an effective sealing of the two. The seal to the outer ring 83 is also through the cement 82 that overlies or extends above the top edge surface of the glass and engages the horizontal leg of the sealing ring 83. The two rings 80 and 83 are mechanically secured together by a series of three to eight inwardly formed lugs 84, sheared from the lower edge of the outer ring and bent inwardly, the said lower edge of the outer ring extending below the bottom of the inner ring and forming a convenient place for the several toggle clamp latch members to hook, as hereinafter explained. The inner edge of the horizontal leg of the sealing ring 83 is preferably bowed up at 85 to form a circular groove above or inside the glass to receive a soft asbestos rope 86 or the like to ensure the glass not touching the ring and to seal the space against entrance of dust and dirt. This rope, however, does not transmit any clamping pressure to the glass.

The assemblage of these parts is thought to be obvious. By the use of suitable jigs the glass is centered in the frame ring 80, the calking cement 82 fills or is filled about and over the edge of the glass as shown in Figs. 9 and 10, the sealing ring 83, preferably painted inside and supplied with the asbestos rope 86, is telescoped down over the frame ring 80, and the tabs 84 at the bottom of the outer ring 83 are bent up under the ring 80. The asbestos rope may be inserted later, if desired. The glass is thus firmly held in the frame.

The upper face of the horizontal leg of the sealing ring 83 forms the lower seat for the gasket 62, is sufficiently strong to carry the clamping and sealing pressure without transferring it to the glass, and is wide enough to receive or engage the gasket in all diameters of the rim. Positive clamping means for clinching the glass frame to the upper reflector element may be used with safety.

The cover is preferably hinged to the gasket mounting element by a readily detachable hinge or hook for convenience in handling, installation, removal and replacement of glass and for other purposes. Thus, Figs. 7, 8, and 10, a metal hinge strap 87 is suitably riveted or otherwise secured 75 to the outside of the outer band ring 66 of the

gasket mounting element, the lower end of which is curved up to form a hook 88 which loosely encircles a formed wire clip 89 or loop attached in any suitable way, as by rivets through its ends, to the outside face of seal ring 83 of the cover frame. This construction provides a safe hinge for the cover and does not interfere with the closing, clamping or opening movements of the cover. A setscrew 90, threading through the outer end of the hook and engaging the strip 87, prevents any undesired separation of the hinge parts, but is readily backed out sufficiently for that purpose so that the cover may be quickly unhinged or unhooked and disconnected from the upper or reflector element.

When the cover is closed it is clamped to its seat on the gasket by a plurality of preferably spring toggle clamps about the edge. In this instance there are six such clamps, located one at each supporting pin 71 of the gasket-retainer segments. They each comprise a spring wire link 91, substantially of the form shown in Fig. 8, hinged or pivoted at one side to the outer band 66 of the reflector element by the clip 92, which may be cut and formed out of the band itself, as indicated, or otherwise secured thereto. The other side of this spring is hinged or rotatably secured to spring link supporting plate, strap or hook 93, which, in the clamped position shown in Fig. 9, engages at its lower upwardly and horizontally bent end 94 the inside of the lower edge of the sealing ring 83 of the cover and presses upwardly against the lower edge of the cover frame member 80. The projecting lower edge of the ring 83 keeps the hooks from slipping outwardly and releasing the cover. The pressure to the gasket above is transmitted directly through the metal parts and does not place the glass under stress. The intermediate portion of the spring hook presses resiliently against the head of the pin 71 and assists in pressing the segment carried by it tightly against the reflector bead. The toggle action of these clamps will be understood. They may be opened by pulling outwardly the upper hinged sides of the spring links 91 and hook plates 93, their resiliency permitting such movement, so that the hooked ends 94 lower and free the cover. They may then hang loosely, as shown in Fig. 8. To clamp the cover in place, the reverse operation takes place. When the cover is closed and in position to be clamped, the link 91 is swung upwardly, the hook 94 steered into position by the same movement, and the upper side or end of the link and hook pressed inwardly toward the reflector. The link 91 will snap into this position because its upper side passes the center line of points 92 and 94, and be maintained in that position until manually released.

The operation is thought to be obvious from the foregoing. In this form, as in the preceding, the gasket is carried on the housing and is always properly seated on the rim to make an ideal seal therewith and possesses the other advantages mentioned. The rim, gasket, frame and glass edge are all substantially in line and give full light opening to the reflector, the glass is cushion-sealed and supported and is not put under strain by the clamping of the cover in closed position. The device is self-adjusting to the different sizes of reflector rims when installed, so that no special manipulation or disassembling and reassembling of parts is required in applying it to do a perfect job. When the single clamping screw is tightened, the gasket fits perfectly and the de-

vice is firmly and tightly secured to the housing. The outer band by its two legs or members envelopes and covers the rim of the housing, the gasket and the edge of the cover so as to protect the same from dust and dirt and to present an unobtrusive and neat appearance. Thus the objects and advantages of the invention as heretofore related and others obvious from an inspection and use of the device, are realized.

With respect to mounting the gasket on the reflector or housing rim instead of on the cover, it may be pointed out that for practical reasons, such as the space taken up, the cost, and the like, a narrow and small cross-section is preferred. A square cross-section, $\frac{1}{4}$ -inch on a side, is ideal for the purpose, and, as shown, is attainable in this invention. Thus, if the gasket were built into or attached to the cover, it would have to be much wider to insure its contacting for the full perimeter of the housing or reflector and the cover, in order to allow for manufacturing tolerances in housing or reflector diameters, for variations in glass diameters, and to provide enough clearance between the glass frame of the cover and the rim of the housing or reflector. Again, the housing or reflector rim may not be a true circle. But if the small cross-sectional gasket is held directly on and positioned so that it must align with the reflector or housing rim, as in this construction, the contact or gasket seat on the cover, which in this invention can be made relatively wide and flat, must strike the gasket at all points on the periphery when the cover is closed. Then, too, the gasket located on the reflector or housing rim becomes a stationary member of the assembly and is better protected from injury in the regular operation of the cover than were it located in the cover frame. Also, if desired, the gasket may be further and more securely attached to the reflector or housing rim by a suitable cement applied between the rim and the adjacent gasket surface and even at the several slits where the retainer tongues pass through it, whereas if the gasket were a part of the cover frame it would be disturbed and likely destroyed at each glass replacement and the trouble and expense of a new gasket incurred. Putting the gasket on the narrow rim of the varying-diameter reflector or housing, even though that rim may be distorted from a true circle, puts the gasket where it must be, to-wit, directly under that rim, where it cannot get away. Where the cover must be attached to the unit by the purchaser, the gasket retainers are split up, as explained, into a series of pieces or segments so mounted and controlled in their radial movement that the gasket is not stretched all at one point from its original length, fitting a minimum-diameter reflector, to that fitting a maximum-diameter reflector, but its stretch is distributed about the circle on the segments. The slits in the gasket, made by forcing a suitable thin knife-edged tool through the gasket wall, are slightly longer than the width of the retainer tongues to allow for possible variations in spacing both of the slits and of the tongues and so that the gasket may slip over the tongues without stretching or forcing. In expanding the segments for the larger-diameter rims, therefore, the slits are long enough to permit the gasket to slide slightly on the tongues in a peripheral direction to assist in distributing the stretch. Moreover, it is possible that where two segment ends abut, the near edge of the tongues on adjacent segments may be close to the near ends of the gasket slits for the minimum-size rim, and as the segments sep-

erate for the larger-size rim, the tongues will have a chance to slide freely in the gasket slits.

The gasket thickness, preferably $\frac{1}{4}$ -inch, being generous, the tongues thin, and the material of the gasket of a resilient, pliable nature, the portions of the slits beyond the width of the tongues will close completely to form watertight closures, particularly when clamped between the reflector rim and the seal ring of the cover.

The number of segments in the gasket retainer ring may be varied as deemed practical and workable. In the old cast-iron reflector with a flat rim and with a simple cover attached by screws, it was found desirable not to space the screws more than nine inches apart around the circumference if one expected to get a good tight clamp or squeeze on the gasket. The present invention provides for one clamp for each gasket-retainer segment. It is deemed desirable, therefore, not to make the segments more than approximately nine inches long. Accordingly, for an 8-inch-diameter reflector, three such sections are found desirable; for a 22-inch reflector, eight segments suffice; and in the 18-inch reflector herein illustrated, there are six such sections or segments. This covers the range of sizes ordinarily manufactured and indicates a practical rule that may be successfully followed for different sizes.

As before pointed out, the hinged cover, as in the detachable form of the device, is readily removable for any desired purpose by taking out the screw 90 and unhooking the cover from the hinge hook 88. The cover in the built-in type may also be quickly removed for any desired purpose, such, for example, as for glass replacement, etc., which may be done readily by taking out one or both of the hinge screws 52 and separating the cover from the rim.

While in this specification the device has been considered in its position as shown in the drawing with its axis vertical, it will be understood that it may be used in any position, and the description and claims should be read and understood accordingly. So, too, the terms "housing" and "reflector" are used synonymously and should be so understood. "Glass," of course, is intended to cover suitable materials for the purpose.

Without further elaboration, the foregoing will so fully explain the gist of this invention that others may, by applying current knowledge, readily adopt the same for use under varying conditions of service without eliminating certain features which may properly be said to constitute the essential items of novelty involved, which items are intended to be defined and secured by the following claims.

I claim:

1. A lighting fixture of the class described comprising a housing having a formed rim around its open end, said rim forming an upper gasket seat, a cover having a glass and a metal frame around the periphery of the glass, said frame having a space around the edge of the glass, cementing material in said space to hold and seal the glass therein, said frame having a sealed ledge extending inwardly over and out of contact with the glass, said ledge forming a lower gasket seat, a gasket between said rim and ledge seats, and means for clamping said frame to the housing at said rim, gasket and ledge to hold and seal the same without putting the glass under strain.

2. A lighting fixture of the class described comprising a housing having a formed rim

around its open end, said rim forming an upper gasket seat, a cover having a glass and a metal frame around the periphery of the glass, said frame having a space around the edge of the glass, cementing material in said space to hold and seal the glass therein, a sealing ring, right-angled in cross-section having its vertical leg secured and sealed to the frame and its horizontal leg extending inwardly and over the glass, but out of contact with same and forming a lower gasket seat, a packing of soft material between the glass and said ring, a gasket between the rim and frame seats, and means for clamping the cover to the housing at said rim, ring and seats without compression or strain of the glass.

3. A lighting fixture of the class described comprising a housing having a formed rim around its open end, said rim forming an upper gasket seat, a cover for said open end having a glass and a metal peripheral frame for the glass, said frame including a ring larger in diameter and deeper than the thickness of the glass and having an inwardly extending raised shelf at its outer edge to engage and support the outer face edge of the glass, a calking cement filling the gutter-like space in the ring and around the edge of the glass to seal and hold the glass in the ring, a seal ring angular in cross-section having one leg portion embedded and sealed in said cement and extending to the said ring so as to be supported thereby, the other leg portion of the seal ring extending inwardly over the glass and spaced above the same and forming at its upper side a lower gasket seat, a gasket between the two seats, and means for sealingly clamping said ring to said rim on said gasket, whereby the clamping pressure is taken by the frame and the glass is free therefrom.

4. A lighting fixture of the class described comprising a housing having a formed rim around its open end, said rim forming an upper gasket seat, a cover for said open end having a glass and a metal peripheral frame for the glass, said frame including a continuous ring of sturdy cross-section and larger in inside diameter and deeper than the thickness of the glass and having an inwardly extending raised shelf at its outer edge to engage and support the outer face edge of the glass, a calking cement filling the substantial gutter-like space in the ring and around the edge of the glass to seal and hold the glass in the ring, a continuous seal ring angular in cross-section having one leg portion embedded and sealed in said cement and extending to the said ring so as to be supported thereby, the other leg portion of the seal ring extending inwardly over the glass and spaced above the same and forming at its upper side a lower gasket seat, a soft filler in the corner between the legs and the corner of the glass, a gasket between the two seats, and means for sealingly clamping said ring to said rim on said gasket, whereby the clamping pressure is taken by the frame and the glass is free therefrom.

5. A sealed-cover construction for light-fixture housings having a formed rim around its open end comprising a glass and a peripheral metal framework therefor, said frame including a continuous ring of sturdy cross-section having a slightly elevated horizontal ledge at the bottom edge on which the outer face edge of the glass lies, the said ring being larger in diameter than the glass and deeper than the glass thickness to provide a substantial space therearound, a filling of plastic cementitious material in said space to

hold and seal the glass therein, and a continuous sheet metal seal ring of inverted L-shaped cross-section having its vertical leg embedded and sealed in said material and extending down to the bottom of the ring, the horizontal leg of said seal ring extending over the glass out of contact therewith and forming at its upper horizontal surface the lower seat for the gasket seal of the cover to the housing rim, whereby the clamping sealing pressure is carried by the metal ring independently of the glass.

6. A sealed cover construction for light-fixture housings having a rim around its open end comprising a glass and a metal frame around the glass, said frame including continuous inner and outer telescoping rings forming a sturdy band around the edge of the glass, the inner ring having a lower portion extending inwardly with an elevated ledge on which the glass lies, the said band being larger in diameter and deeper than the glass to provide a substantial space around the edge of the glass, and a filling of plastic cementitious material in said space to seal and hold the glass therein, the outer ring having a horizontal portion extending inwardly over the glass above and out of contact therewith but engaged on the lower side and sealed in position by said filling, the upper face of said horizontal portion forming the lower seat for the gasket seal of the cover to the housing rim, whereby the clamping sealing pressure of the cover to the housing is carried by the frame without compressing the glass.

7. A sealed cover construction for light-fixture housings having a rim around its open end comprising a glass and a metal frame around the glass, said frame including continuous inner and outer telescoping rings sealed together, forming a sturdy band around the edge of the glass, the inner ring having a lower portion extending inwardly with an elevated ledge on which the glass lies, the said band being larger in diameter and deeper than the glass and providing a substantial space around the edge of the glass, a filling of plastic cementitious material in said space to seal and hold the glass therein, the outer ring having a horizontal portion extending inwardly over the glass above and out of contact therewith but engaged on the lower side and sealed in position by said filling, the upper face of said horizontal portion forming the lower seat for the gasket seal of the cover to the housing rim, whereby the clamping sealing pressure of the cover to the housing is carried by the frame without compressing the glass, a packing of soft material between the inner edge of the horizontal portion of said sealing ring and the surface of the glass, the lower edge of the sealing ring extending below the inner ring and forming a convenient place for hooking clamping devices, and inwardly bent lugs cut from said lower edge to mechanically secure said rings together.

8. A lighting fixture of the class described comprising a housing having a rim formed about its open end forming an upper gasket seat, a cover for said open end having a lower gasket seat, a ring of gasket material between said seats adapted to be engaged and sealingly compressed thereby, and a gasket-retaining strip carried by the housing and surrounding said rim and gasket and having tongues extending through said gasket between the seats and bent upwardly at the inside of the gasket and securing the gasket to its rim seat, whereby the gasket is sealingly compressed between said seats when the cover is closed and

remains attached to its rim seat when the cover is opened.

9. A lighting fixture of the class described comprising a housing having a rim formed about its open end forming an upper gasket seat, a cover for said open end having a lower gasket seat, a ring of gasket material between said seats adapted to be engaged and sealingly compressed thereby, and a sheet metal gasket-retaining strip outside said rim and gasket and secured thereto, the lower edge of said strip being notched to form tongues, said tongues being bent inwardly and extending through slits in the gasket ring between its upper and lower seating faces, said tongues being further bent upwardly at the inside of the gasket ring with their ends extending above the upper gasket seat, whereby the gasket ring is confined to its rim seat on the housing and the cover may be opened and closed without disturbance thereof or thereby.

10. A lighting fixture of the class described comprising a housing having a rim formed about its open end forming an upper gasket seat, a cover for said open end having a lower gasket seat, a ring of gasket material between said seats adapted to be engaged and sealingly compressed, and a sheet metal gasket-retaining band surrounding said rim and attached thereto, the lower edge of said band having tongues formed thereon bent to extend horizontally inward, the gasket being impaled on said tongues and held thereby to its rim seat, the tongues being bent upwardly at the inside face of the gasket, with their ends extending above the rim seat, whereby the gasket is centered and retained in proper position on the rim seat.

11. A lighting fixture of the class described comprising a housing having a formed rim at the open end, said rim forming an upper gasket seat, a ring of gasket material substantially rectangular in cross-section on said seat, a sheet metal gasket-retaining ring strip outside said rim and gasket, said gasket having slits punched horizontally therethrough at regular spaced intervals, the lower edge of said gasket-retaining strip having tongues formed thereon bent horizontally and extending through said gasket slits and then bent upwardly at the inner side of the gasket and with their ends reaching above the said rim seat, whereby properly to seat and maintain the gasket on its said rim seat, means for securing said retaining strip to the said rim, and a cover for the open end of the housing having a lower gasket seat to sealingly engage said gasket when the cover is secured in place thereon.

12. A lighting fixture of the class described in which the housings may differ in diameter within a manufacturing tolerance range, comprising a housing having a rim around its open end forming a gasket seat, a ring gasket normally of a size properly to fit such a seat of the smallest diameter, means for stretching said gasket properly to fit on the seats of larger rims, and a cover for said open end of the housing having a gasket seat properly to engage and compress said gasket, whatever its size, when the cover is closed.

13. A lighting fixture of the class described in which the housings may differ in diameter within a manufacturing tolerance range, comprising a housing having a rim around its open end forming a gasket seat, a ring gasket normally of a size properly to fit such a seat of the smallest diameter, means for controllably stretching said gasket properly to distribute the stretch of the gasket and cause it to fit on the seats of larger

rim, and a cover for said open end of the housing having a gasket seat properly to engage and compress said gasket, whatever its size, when the cover is closed.

14. A lighting fixture of the class described in which the housings may differ in diameter within a manufacturing tolerance range, comprising a housing having a rim around its open end forming a gasket seat, a ring gasket normally of a size properly to fit such a seat of the smallest diameter, a support for the gasket, means for expanding said support and stretching said gasket to fit larger sizes of said rim seat, and a cover for the open end of the housing having a seat for said gasket in any size to sealingly compress the same when the cover is finally closed.

15. A lighting fixture of the class described in which the housings may differ in diameter within a manufacturing tolerance range, comprising a housing having a rim around its open end forming a gasket seat, a ring gasket normally of a size properly to fit such a seat of the smallest diameter, a support for the gasket, means to secure said support and gasket to the rim, means for expanding said support and stretching said gasket to fit larger sizes of said rim seat, means for controlling and distributing the stretch of said gasket, and a cover for the open end of the housing having a seat for said gasket in any size to sealingly compress the same when the cover is finally closed.

16. In a sealed cover construction for light-fixture housings in which the diameters of the open ends may vary in the manufacture thereof, a gasket to seat on the rim of the open end of the housing and of a length normally to reach entirely around the smallest-sized rim, and a gasket-retaining means to confine said gasket to its seat on the rim in position to be engaged by the cover, said retaining means being expansible and contractible to expand and contract said gasket to fit it to the varying sizes of rims.

17. In a sealed cover construction for light-fixture housings in which the diameters of the open ends may vary in the manufacture thereof, a gasket to seat on the rim of the open end of the housing and of a length normally to reach entirely around the smallest-sized rim, and a segmental gasket-retaining means surrounding the gasket and rim and having tongues projecting through the gasket and confining same to the rim, said segments being moved outwardly by a larger rim in the act of applying the construction thereto to stretch and adapt the gasket and segments to the larger rim and to maintain the gasket properly seated thereon.

18. In a sealed cover construction for light-fixture housings in which the diameters of the open ends may vary in the manufacture thereof, a gasket to seat on the rim of the open end of the housing and of a length normally to reach entirely around the smallest-sized rim, a segmental gasket-retaining means surrounding the gasket and rim and having tongues projecting through the gasket and confining same to the rim, said segments being moved outwardly by larger rims in the application of the construction thereto to stretch and adapt the gasket and segments to the larger rims and to maintain the gasket properly seated thereon, and means for controlling the movement of said gaskets to limit the same therebetween.

19. In a sealed cover construction for light-fixture housings in which the diameters of the open ends may vary in the manufacture thereof,

a gasket to seat on the rim of the open end of the housing and of a length normally to reach entirely around the smallest-sized rim, a segmental gasket-retaining means surrounding the gasket and rim and having tongues projecting through the gasket and confining same to the rim, means to move the retaining segments outwardly by the engagement thereof with larger rims when installing the same thereon to stretch and adapt the gasket and segments to the larger rims and to maintain the gasket properly seated thereon, and thin metal strips overlapping the adjacent edges of the segments and mounted on the tongues of each segment near the said edges, the apertures in the strips being longer than the width of the tongues and serving to limit and equalize the expansion between segments and prevent overstretching the gasket.

20. In a sealed cover construction for light-fixture housings in which the diameters of the open ends may vary in the manufacture thereof, a gasket to seat on the rim of the open end of the housing and of a length normally to reach entirely around the smallest-sized rim, a gasket-retaining means to confine said gasket to its seat on the rim in position to be engaged by the cover, said retaining means being expansible and contractible to expand and contract said gasket to fit it to the varying sizes of rims, an outer band enclosing said retaining means and connected thereto to position and retain the same on the rim, said band being expansible to permit same and the retaining means to be slipped over the rim of the housing, and means to tighten the band about the housing to secure the same and the gasket-retaining means thereto.

21. In a sealed cover construction for light-fixture housings in which the diameters of the open ends may vary in the manufacture thereof, a gasket to seat on the rim of the open end of the housing and of a length normally to reach entirely around the smallest-sized rim, a segmental gasket-retaining means surrounding the gasket and rim and having tongues projecting through the gasket and confining same to the rim, an outer expansible band enclosing and carrying said retaining means, said band having an inwardly extending upper edge portion extending over the rim when the band is tightened about the housing for holding it together with the gasket and connected parts firmly on the housing, said band when loosened and expanded withdrawing its upper flange from over the said rim to permit the device to be detached from the housing or to be applied thereto and upon further expansion to enable the segments to move radially outward to fit them to larger rims, and means for tightening and loosening said expansible band.

22. In a sealed cover construction for light-fixture housings in which the diameters of the open ends may vary in the manufacture thereof, a gasket to seat on the rim of the open end of the housing and of a length normally to reach entirely around the smallest-sized rim, a gasket-retaining means to confine said gasket to its seat on the rim in position to be engaged by the cover, said retaining means being divided into a plurality of segments, an expansible outer band surrounding the segments and connected therewith to support and control the same, said connection including a headed pin for each segment extending through a longitudinal slot in the band and into the segment intermediate its ends, leaf springs secured to the inside of the band and

each overlapping and slidably bearing at its ends against adjacent segments near their ends, said springs tending to press the segments inwardly and the band outwardly, said band being severed at one point, and a clamping and expanding screw connecting the ends thereof, the said springs causing the band to expand substantially equally about the segments, the pins, sliding in the slots during such expansion, and when the band is tightened the reverse action takes place, the segments being pressed inwardly, the segments thus traveling radially from the one position to the other.

23. In a sealed cover construction for light-fixture housings in which the diameters of the open ends may vary in the manufacture thereof, a gasket to seat on the rim of the open end of the housing and of a length normally to reach entirely around the smallest-sized rim, a gasket-retaining means to confine said gasket to its seat on the rim in position to be engaged by the cover, said retaining means being expansible and contractible to expand and contract said gasket to fit it to the varying sizes of rims; an outer band enclosing said retaining means and connected thereto to position and retain the same on the rim, said band being expansible to permit same

and the retaining means to be slipped over the rim of the housing, and means to tighten the band about the housing to secure the same and the gasket-retaining means thereto, said tightening means consisting of a thumb-screw connecting the ends of the band, the band when tightened by the screw concealing and drawing together the gasket-retaining and positioning parts, closely gripping the housing and forming a rigid, substantial anchorage for the movable cover element.
